UNITED STATES PATENT OFFICE.

PAUL VANDIVER, OF CHICAGO, AND JOSEPH W. HESS, OF MELROSE PARK, ILLINOIS,
ASSIGNORS TO SOLAR-STURGES MFG. CO., A CORPORATION OF ILLINOIS.

RECEPTACLE CLOSURE.

Application filed April 13, 1923, Serial No. 631,763. Renewed November 17, 1924.

To all whom it may concern:

Be it known that we, PAUL VANDIVER and JOSEPH W. HESS, citizens, respectively, of the United States and the Republic of Poland, residing, respectively, at Chicago, in the county of Cook and State of Illinois, and at Melrose Park, in the county of Cook and State of Illinois, have jointly invented certain new and useful Improvements in Receptacle Closures, of which the following is a specification.

This invention relates to a new and improved receptacle closure and more specifically to a closure for receptacles which closure is adapted to be readily displaced to clear the opening and to automatically return to close the opening.

Receptacles of this character are particularly adapted for use to receive garbage, paper, waste or other material of this character. An automatic closure is desirable in order that the receptacle may be closed at all times to prevent displacement of the material, to cover its unsightly appearance, and to prevent access by flies or the like.

It is an object of the present invention to provide a universally movable closure for receptacles, adapted to be readily displaced and to automatically return to the closed position.

It is a further object to provide a device of this character in which the displacement may be in any direction with equal facility.

It is an additional object to provide a construction composed of but few and simple parts adapted for inexpensive commercial production and adapted for association with existing receptacles without modification thereof.

We have illustrated a preferred embodiment of our invention in the accompanying drawings in which:

Figure 1 is an elevation showing the closure assembly applied to a receptacle;

Figure 2 is a vertical section of the closure assembly in the upper portion of a receptacle with the closure in normal position; and

Figure 3 is a view similar to Figure 2, but showing the closure in a displaced position.

The receptacle 5 is shown as a usual type of cylindrical can or drum for receiving material of any kind. The supporting mem-

ber 6 which is placed upon the upper end of the receptacle is provided with the outwardly and downwardly extending apron 7 and the cylindrical or tubular sleeve 8, which fits down within the upper end of the receptacle. It will be observed that the underside of the skirt 7 rests upon the upper edge of the receptacle and maintains the closure assembly in position on the receptacle. The spider 9 is connected to the inner side of the tubular portion 8 and is provided with a central portion 10 having a vertical opening therein, which opening receives the screw 11. The pivot member 12 has its lower end resting upon the portion 10 and its inner surface is threaded to receive the screw 11 which secures it rigidly in place upon the spider. The closure member 13 is conical in shape and is provided at its upper edge with an inturned flange 14 which rests upon the upper end of the pivot member 12. The lower edge of the closure 13 extends closely adjacent the meeting edge between the skirt 7 and cylindrical portion 8 of the supporting member.

The screw 15 is threaded into the upper end of the pivot member 12 forming an upward extension of that member and passing through a central opening in the closure 13. The coil spring 16 surrounds the shaft 8 of the screw 15 bearing at one end against the underside of the enlarged head of the screw and at the other end upon the inturned flange 14 of the closure.

The central opening in the closure 13 is made of such size as to afford adequate clearance between it and the shaft of the screw 15 so that the closure may be tilted to a position such as that in which it is shown in Figure 3. The spring 16 aids in returning the closure to the closed position and also practically eliminates swinging of the closure beyond the closed position. It is obvious, however, that the closure will return by gravity to the closed position without the assistance of the spring.

The closure being balanced upon its central support may be readily displaced with but slight pressure in order to clear a substantial portion of the upper opening of the receptacle for the introduction of matter therein. This introduction may take place from any direction which feature is of con-

siderable importance in permitting a receptacle closure of this construction to be used in any location.

The closure and its supporting member have been shown as formed separately from the receptacle proper and when so formed obviously the supporting member 6 as well as the closure may be removed when emptying the receptacle. Also the closure assembly is itself independent of the receptacle and may be readily removed from a filled receptacle and placed upon an empty one whereupon the filled receptacle may be closed by any usual type of cover and removed.

We have illustrated one preferred embodiment of our invention which is obviously capable of modification to meet varying conditions. It is our intention to cover such modifications as come within the scope of the appended claims.

We claim:

1. In a receptacle closure, supporting means, a closure member supported thereon and adapted for universal movement relative to the support, and a spring engaging the closure and adapted to resist movement thereof from the normal position.

2. In a receptacle closure, supporting means, a closure member supported thereon and adapted for universal movement relative to the support, and a spring engaging the closure adjacent its point of engagement with the support and adapted to resist movement thereof from the normal position.

3. In a receptacle closure, a vertically extending pivot, a conical closure member having its upper portion resting on said pivot and adapted for universal movement relative to said pivot, and spring means carried by the pivot and engaging the closure member to resist displacement of the closure member from normal position.

4. In a receptacle closure, a pivot member having a seat thereon, a reduced portion extending above the seat, and a closure fitted on said seat and having an opening permitting passage of the reduced portion of the pivot member, the opening providing clearance between the closure and reduced portion sufficient to permit universal tilting of the closure relative to the pivot.

5. In a receptacle closure, a pivot member having a seat thereon, a reduced portion extending above the seat, and a closure fitted on said seat and having an opening permitting passage of the reduced portion of the pivot member, an enlarged head on said reduced portion and a spring encircling the reduced portion between the head and closure member and serving to yieldingly resist displacement of the closure member.

6. In a receptacle closure, a pivot mem-

ber having a seat thereon, and a closure member having a downwardly extending body portion, a central opening, and an inturned downwardly extending flange surrounding said opening and adapted to engage the pivot seat and make line contact therewith.

7. In a receptacle closure, a pivot member having a seat thereon, a closure member having a downwardly extending body portion, a central opening, and an inturned downwardly extending flange surrounding said opening and adapted to engage the pivot seat and make line contact therewith, an upwardly extending member carried by the pivot extending through the closure opening, and a spring carried by said member and seated on the inturned closure flange and adapted to yieldingly resist displacement of the closure.

8. A closure assembly comprising a supporting member adapted to be seated upon the upper edge of an open topped receptacle, the member comprising a tubular portion extending within the receptacle, and a skirt portion overhanging the receptacle edge, a spider extending transversely of the opening of the tubular portion, a pivot member extending vertically upward from the central portion of the spider, and a closure member supported on said pivot in such manner as to normally close the opening and to be movable in any direction upon the pivot to clear a portion of the opening, and a spring carried by the pivot member and engaging the closure member to yieldingly maintain it in closed position.

9. A closure assembly comprising a supporting member adapted to be seated upon the upper edge of an open topped receptacle, the member comprising a tubular portion extending within the receptacle, and a skirt portion overhanging the receptacle edge, a spider extending transversely of the opening of the tubular portion, a pivot member extending vertically upward from the central portion of the spider, and a closure member supported on said pivot in such manner as to normally close the opening and to be movable in any direction upon the pivot to clear a portion of the opening, the closure having a central perforation, a portion of the pivot member extending upwardly through said perforation, and a spring carried by the upwardly extending pivot portion and engaging the upper face of the closure member to yieldingly maintain it in closed position.

Signed at Chicago, Illinois, this 10th day of April 1923.

PAUL VANDIVER.
JOSEPH W. HESS.
